United States Patent Office

Des. 194,898
Patented Mar. 26, 1963

194,898

LUGGAGE CASE

Harold C. Wells, Arlington, Mass.

Filed Feb. 7, 1962, Ser. No. 68,700

Term of patent 14 years

(Cl. D87—5)

Fig. 1.

Fig. 2.

Fig. 3.

I claim:

The ornamental design for a luggage case, substantially as shown.
